(57) **CLAIM**

The ornamental design for an alternator, as shown and described.

DESCRIPTION

FIG. 1 is a front, top, left-side perspective view of an alternator showing our new design;

FIG. 2 is a left-side elevational view thereof;

FIG. 3 is a top plan view thereof;

FIG. 4 is a rear elevational view thereof;

FIG. 5 is a front elevational view thereof;

FIG. 6 is a right-side elevational view thereof; and,

FIG. 7 is a bottom plan view thereof.

The broken lines depict environmental subject matter only and form no part of the claimed design.
